UNITED STATES PATENT OFFICE.

FREDERICK T. WRIGHT, OF DOUGLAS, ARIZONA TERRITORY.

SURGICAL INSTRUMENT.

No. 866,995.

Specification of Letters Patent.

Patented Sept. 24, 1907.

Application filed June 15, 1907. Serial No. 379,210.

To all whom it may concern:

Be it known that I, FREDERICK T. WRIGHT, a citizen of the United States, residing at Douglas, in the county of Cochise and Territory of Arizona, have invented certain new and useful Improvements in Surgical Instruments, of which the following is a specification.

My invention relates to certain new and useful improvements in first aid packages, and the object of my invention is to provide a device which can be conveniently carried in the pocket, and which is particularly adapted for the treatment of wounds inflicted by venomous snakes or the like.

By my invention I have provided a device which is simple in construction, composed of few parts, is durable and which can be conveniently carried by any person; at the same time the device can be opened without delay.

Referring to the drawings wherein I show the preferred form of my invention and wherein the same part is designated by the same reference numeral wherever it occurs, Figure 1 is a perspective view of the device in its closed condition; Fig. 2 is a central longitudinal section of Fig. 1, and Fig. 3 is a perspective view of the parts thereof separated.

1 designates a tube which is formed of any suitable metal, and provided with a transverse partition 2 dividing the tube into two compartments 3 and 4. Each end of the tube on its interior is screw threaded as shown at 5.

6 designates a plug having a screw thread so that it can be screwed into one end of the tube to close the compartment 3. Preferably, and as shown, this plug is provided with an enlarged milled head 7, whereby the plug can be readily removed from the end of the tube and which, when the plug is screwed down tightly in place forms a tight joint.

8 designates a second plug, the body of which is preferably of the same diameter as the tube 1, and provided at one end with a reduced portion 9, which is 40 screw threaded, whereby the plug may be screwed in the end of the tube. At the end of the plug, opposite the reduced portion 9, I preferably produce an enlarged milled head 10, whereby the plug may be read-

ily unscrewed from the end of the tube. Secured to the end of the reduced portion 9 of the plug is a lance 11. 45

In the operation of my device the compartment 3 is filled with an antidote for the venom of the particular reptile which is feared, such for instance, for rattle snakes, as a mixture of permanganate of potash and sulfate of strychnine. The plug 6 is now secured in 50 the compartment end of the tube closing the compartment and the plug 8 on which the lance is mounted is secured in place in the other end. The device can now be carried in the pocket, and when a person is bitten the plug 8 is unscrewed from the tube and the 55 lance used to scarify the wound and cause a free flow of blood therefrom. The other end of the tube is then opened, and the antidote taken out and rubbed into the wound.

While I have described what I believe to be the 60 preferred form of my invention, I desire to have it understood that many changes may be made in the form, construction and arrangement of parts without departing from the spirit of my invention.

What I claim as new and desire to secure by Letters 65 Patent is

1. The combination with a tube having a partition therein dividing the same into two compartments, of a plug for closing the end of one of said compartments and carrying a lance inserted into the compartment closed by said 70 plug, and a plug inserted into and closing the end of the other compartment whereby the same is adapted to contain a remedy.

2. The combination with a tube having a partition therein dividing the same into two compartments, the ends of the tube being internally screw threaded, of a plug provided with a screw threaded end, a lance mounted on the plug, said plug being adapted to be inserted into one end of said tube into one of the compartments and to close the end of the same, a screw threaded plug adapted to be 80 inserted in the other end of said tube and to close the end of the same, whereby the other compartment is adapted to contain a remedy.

In testimony whereof I affix my signature in presence of two witnesses.

FREDERICK T. WRIGHT.
